US0D1034331S

(12) **United States Design Patent** (10) Patent No.: **US D1,034,331 S**
(45) Date of Patent: ** Jul. 9, 2024

(54) **ELECTRIC BICYCLE**

(71) Applicant: **Invanti (Beijing) Technology Co., Ltd**,
Beijing (CN)

(72) Inventor: **Chongyang Shi**, Beijing (CN)

(73) Assignee: **INVANTI (BEIJING)**
TECHNOLOGY CO., LTD, Beijing
(CN)

(**) Term: **15 Years**

(21) Appl. No.: **29/884,777**

(22) Filed: **Feb. 16, 2023**

(30) **Foreign Application Priority Data**

Dec. 13, 2022 (CN) 202230833690.4

(57) **CLAIM**

The ornamental design for an electric bicycle, as shown and described.

DESCRIPTION

FIG. 1 is a perspective view of an electric bicycle showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
